UNITED STATES PATENT OFFICE.

ALBERT B. GLISSON, OF SYRACUSE, NEW YORK, ASSIGNOR TO THE PROSPERITY COMPANY, INC., OF SYRACUSE, NEW YORK, A CORPORATION OF NEW YORK.

SPRING PAD.

Application filed February 24, 1926. Serial No. 90,424.

This invention has for its object a spring pad for pressing machines, or a pressing machine having a spring pad and means for tying together the upper ends of coiled springs 5 of a group and also for securing them to a top plate and for limiting the compression of the springs so that the amount of final pressure delivered is not dependent upon the strength of the springs, but is dependent upon the 10 force applied to the movable pressing element or head.

The invention further consists in a spring pad construction embodying means for limiting the compressing of the springs, and the 15 use of a comparatively small number of springs rather than a great number of comparatively small springs.

The invention consists in the novel features and in the combinations and constructions 20 hereinafter set forth and claimed.

In describing this invention reference is had to the accompanying drawings.

Figure 1 is a fragmentary elevation of a pressing machine embodying my invention.

Figure 2 is a fragmentary side elevation of 25 this pad.

Figure 3 is a plan view of a group of four springs showing the means for attaching a group to the plate.

Figure 4 is a fragmentary plan face of the 30 pad seen in Figure 2.

Figure 5 is a plan view of a group of springs illustrating the tie plate connecting the springs.

Figure 6 is an elevation of the detached 35 pad.

Figure 7 is an inverted plan view partly broken away.

Figure 8 is a detail view of the tie plate.

40 The spring pad usually consists of two plates, spaced apart and springs located between them. 1 and 2 designates these plates, and 3 the springs located between them, the springs being arranged in groups and each 45 group as here shown comprising four springs. The groups are spaced apart or located at intervals throughout the area of the plates 1 and 2 so that a comparatively small number of springs are used and these springs are

50 stiffer compared with those of the spring pads in which the springs cover the entire area of the plates.

In spring pads heretofore used it has been necessary to use numerous springs in order 55 to withstand the pressure and even then the

springs were often crushed beyond their elastic limit. In order to prevent crushing of the springs and also to limit the elasticity of the pad so that full pressure can be applied, stops are provided for limiting the compression of the springs or limiting the relative movement of the plates 1 and 2. As here shown the plate 1, which is a top plate is provided with stop shoulders 4 depending therefrom toward the bottom plate 2, these shoulders being secured to the plate 1 at intervals as by screws 60

5. In Figures 2 and 4 the springs are shown as arranged in pairs, and in Figures 3 and 5 the springs are shown as arranged in groups of four, each group consisting of two pairs. 70

The springs of each pair are connected by an integral wire connector 7 forming an extension of the coils of the springs. The connectors of the two pairs of each group are arranged side by side and secured to the plate 75 1 as by a forked or bifurcated rivet 8 embracing the connectors 7, and extending through a hole in the plate 1, and clinched on the top side of the plate 1. The plate 1 is also preferably perforated throughout its area as at 9. 80

The outer or lower ends of the springs are preferably connected together or those of each group are connected together as by a tie plate 10. This tie plate extends under the lowermost coils of the springs of each group, and is bent or hooked as at 11 to interlock with the springs. In the illustrated embodiment of my invention the tie plates 10 are secured to the face plate 2 by screws 12 extending through holes in the face plate 90 2 and threaded into the tie plates 10, the tie plates being usually provided with bosses 13 secured thereto.

In Figure 1 the pad is shown as mounted upon the buck 14 of a pressing machine, and 95 is compressed by the head 15 of the machine. The spring pad is covered over with fabric pad 16, and wrapper 17.

In operation when the pressure is applied, it is first yieldingly applied by the head 15 as the springs compress. However, the yielding of the springs is limited by the stops 4 so that the full pressure of the machine can be applied without crushing or destroying the springs. 100

By this invention comparatively few in number of relatively strong springs can be used, leaving a large hollow space within the padding to form a suction chamber to draw the moisture out of the padding through the 110

perforations 9 when the springs expand as the pressure is released.

What I claim is:—

1. A pad for pressing machines, comprising opposing plates, springs between the plates, and stops projecting from one of the plates toward the other and being of less length than the springs the stops being distributed over the area of the plate from 10 which they project.

2. A pressing machine pad comprising a plate, groups of compression springs secured at like ends to the plate, and means for tying the other ends of each group of 15 springs together, said means comprising a plate interlocked with the end coils of the springs of each group.

3. A pad comprising a plate, springs arranged in groups and secured at like ends 20 to the plate and means for fastening the other ends of the springs of each group together, comprising a tie plate extending under the outermost coils of the springs, and having hooks located within the springs for interlocking within such coils.

4. A pad comprising a plate, springs arranged in groups and secured at like ends to the plate and means for fastening the other 25 ends of the springs of each group together,

comprising a tie plate extending under the outermost coils of the springs, and having hooks located within the springs for interlocking within such coils, a face plate underlying the tie plates and fastening means extending through the face plate into the tie 30 35 plates.

5. In a pressing machine pad comprising a plate, groups of compression springs secured at like ends to the plate, the groups being spaced apart a greater distance than the 40 springs of each group and stops located in the spaces between the groups for limiting the compression of the springs.

6. A pressing machine pad comprising a plate, groups of compression springs secured 45 at like ends to the plate, the groups being spaced apart a greater distance than the springs of each group, a plate interlocked with the end coils at the other ends of the springs of each group, and a third plate opposed to the second mentioned plates, and means for fastening the third plate and the second mentioned plate together.

In testimony whereof, I have hereunto signed my name, at Syracuse, in the county 55 of Onondaga, and State of New York, this 6th day of February, 1926.

ALBERT B. CLISSON.
